LOCKING-BOLT ACTUATING MEANS FOR
MACHINE GUNS

Thomas R. Robinson, Jr., New Haven, Conn., assignor to The High Standard Manufacturing Company, Incorporated, Hamden, Conn., a corporation of Connecticut

Application March 9, 1943, Serial No. 478,489

2 Claims. (Cl. 89—3)

The present invention relates to improvements in machine guns and relates more particularly to the actuating-means for effecting the retirement of the locking-bolt which serves to lock the breech-bolt in its breech-closing position to thereby permit the retirement of the said breech-bolt away from its breech-closing position.

In machine guns the rapidity of operation of the mechanism (very often more than one thousand cycles per minute) imposes great stresses on the actuating-means which serves to retire the locking-bolt to thereby permit the movement of the breech-bolt out of its breech-closing position, and one of the objects of the present invention is to provide a superior actuating-means which will withstand such strains over long periods of use and under conditions where speeds are approaching the maximum.

Another object of the present invention is to provide a machine gun with superior locking-bolt actuating-means which will withstand the severe strains imposed upon it but which at the same time may be assembled with rapidity and economy and without requiring excessively-skilled workmen.

A further object of the present invention is to provide a machine gun with superior locking-bolt actuating-means which is mounted for slight pivotal movement and in which the pivot-means is so constructed and arranged as to effectively resist the shocks imposed upon the locking-bolt actuating-means by the rapid and long-continued operation of the machine gun.

With the above and other objects in view, as will appear to those skilled in the art from the present disclosure, this invention includes all features in the said disclosure which are novel over the prior art and which are not claimed in any separate application.

In the accompanying drawings, in which certain modes of carrying out the present invention are shown for illustrative purposes:

Fig. 1 is a view in side elevation of a machine gun equipped with the present invention;

Fig. 2 is a broken view partly in side elevation and partly in vertical central-longitudinal section of the rear-portion of the machine gun shown in Fig. 1 with the parts shown in the positions which they assume when the breech-bolt is in its normal breech-closing position;

Fig. 3 is a view corresponding to Fig. 2 but showing the parts in the positions which they assume when the barrel and barrel-extension have recoiled to substantially the limit of their rearward travel and the breech-bolt has been un-

locked and moved rearwardly with respect to the barrel-extension;

Fig. 4 is a broken transverse sectional view taken on the line 4—4 of Fig. 2;

Fig. 5 is a broken view of the forward-portion of the buffer-housing together with the locking-bolt depressors therein;

Fig. 6 is a view mainly in top or plan elevation and partly in section taken on the line 6—6 of Fig. 5;

Fig. 7 is a transverse sectional view taken on the line 7—7 of Fig. 5;

Fig. 8 is a broken perspective view of the forward-portion of the buffer-housing, detached;

Fig. 9 is a similar view of one of the locking-bolt depressors, detached; and

Fig. 10 is a perspective view of one of the pivot-studs, detached.

The particular machine gun herein chosen for purposes of illustrating one form of the present invention is of the so-called "Browning" type and is of the general type illustrated in detail in United States Patent No. 1,628,226, dated May 10, 1927.

As before noted the present invention relates to the means whereby the locking-bolt which locks the breech-bolt in its breech-closing position, is actuated for releasing such breech-bolt, and therefore only the said features plus related features will be described herein.

The machine gun illustrated in the accompanying drawings includes a receiver generally designated by the reference character 15, an axially-reciprocating barrel 16, a barrel-extension 17, a breech-bolt 18 and a perforated barrel-jacket 19.

The barrel 16 has its rear portion extended within the receiver 15 for reciprocation therein and the aforesaid barrel-extension 17 is organized with the rear end of the barrel for reciprocation also within the receiver 15, in a manner well known in the art. The breech-bolt 18 is guided for longitudinal reciprocation relative to the barrel-extension 17 by being fitted into a longitudinal upwardly-opening guide-channel 20 formed in the upper face of the barrel-extension 17, and is normally yieldingly urged forwardly into its breech-closing position by a helical breech-closing spring 21.

In its under face adjacent its rear end, the breech-bolt 18 is formed with a transversely-extending and downwardly-opening locking-groove 22 having a rearwardly-and-upwardly-sloping transverse locking-abutment 23 which faces generally rearwardly and downwardly.

The barrel-extension 17 is formed at its rear with a depending-lug 24 which is formed with a vertical guideway 25 having its upper end intersecting the longitudinal guide-channel 20 in which the breech-bolt 18 reciprocates. At its lower end the vertical guideway 25 intersects a longitudinal downwardly-opening groove 26 formed in the under face of the lug 24 of the barrel-extension 17, as is indicated in Figs. 2, 3 and 4.

Mounted for vertical reciprocation in the vertical guideway 25 in the barrel-extension 17, is a locking-bolt 27 which has its forward upper corner upwardly and rearwardly sloped to provide a cam-like locking-abutment 28 facing in a direction which is generally forwardly and upwardly and corresponding in slope to the locking-abutment 23 of the breech-bolt 18.

Projecting outwardly from each of the respective opposite sides of the locking-bolt 27 is one of two actuating-pins 29-29, each of which extends outwardly through one of two similar vertical clearance-slots 30-30 formed respectively in the adjacent side walls of the lug 24 of the barrel-extension 17. Each of the clearance-slots 30-30 intersects the adjacent one of two longitudinal clearance-recesses 31-31 respectively formed in the opposite side faces of the depending-lug 24 of the barrel-extension 17 and each intersecting the rear face of the said lug.

Rigidly secured to the upper face of the bottom wall of the receiver 15 is a block 32 extending longitudinally in the downwardly-opening longitudinal groove 26 in the bottom face of the lug 24 of the barrel-extension 17. The forward portion of the block 32 is formed with an upwardly-projecting lifting-lug 33 having a rearwardly - and - downwardly - inclined rear face adapted for cam-like engagement with the forward lower corner of the locking-bolt 27 before referred to.

Located in the lower rear portion of the interior of the receiver 15 at a point to the rear of the depending-lug 24 of the barrel-extension 17 is a bar-like housing 34 suitably anchored in place within the said receiver.

As is shown particularly well in Figs. 5, 6 and 8, the housing 34 includes two side-walls 35-35 both projecting forwardly beyond the top-wall 36 thereof. Each of the said side-walls 35-35 is formed in its outer face with a longitudinal groove-like recess 37 intersecting the forward edge of the particular side-wall in which it is formed, and at its rear end communicating with a transverse cylindrically-contoured passage or socket 38. In both its upper and lower walls, each of the recesses 37 before referred to is formed with a central-longitudinal retaining-groove 39. The retaining-groove in the upper wall of each of the recesses 37 is downwardly-opening and intersects the forward end of the side-wall 35 in which it is formed, while the retaining-groove 39 in the complementary lower wall of each of the recesses 37 opens upwardly and, in turn, intersects the forward end of the said side-wall.

The transverse cylindrically-contoured passage 38 in each of the side-walls 35 of the housing 34 extends completely through such side-wall and has a diameter substantially corresponding to the vertical distance between the respective bottoms of the complementary retaining-grooves 39-39 in a given side-wall 35.

Mounted in each of the two longitudinal recesses 37 is one of two complementary bolt-de-

pressing arms 40 which also extends into the outer portion of the adjacent transverse passage 38 and has a cylindrically-contoured rear end 41 conforming thereto.

The rear portion of each of the bolt-depressing arms 40 is formed with two central-longitudinal retaining ribs 42-42 respectively formed on its upper and lower edges and sized to have a sliding fit within the pair of complementary retaining-grooves 39-39 in one of the two recesses 37 respectively formed in the side-walls 35-35 of the housing 34. The vertical distance between the outer surfaces of a given pair of complementary retaining-ribs 42-42 is materially less than the vertical distance between the bottoms of the complementary pair of retaining-grooves 39-39 in the particular recess 37 in which the bolt-depressing arm fits, so that the forward ends of the said arms may have vertical swinging movement for purposes as will hereinafter appear and as indicated by broken lines in Fig. 5. At its extreme rear end the inner face of each of the bolt-depressing arms 40 is formed with a notch 42a arranged concentric with a transverse bore 43 and flush with the plane of the two complementary retaining-ribs 42-42, as is especially well shown in Fig. 9. Seated in the notch 42a of each of the respective bolt-depressing arms 40 is the cylindrically-contoured head 44 of a retaining-stud generally designated by the reference character 45 and including also an integral relatively-slender shank 46 projecting concentrically from one face of the said head 44. The shank 46 projects outwardly through the bore 43 in the arm 40 of which it forms a part and is swaged over at 47 to rigidly unite the stud with the appropriate arm.

The head 44 of a given retaining-stud 45 has a diameter appropriate for a smooth turning fit in the cylindrically-contoured passage or socket 38 in which it fits and has a thickness in an axial direction sufficient to project inwardly from the notch 42a of its arm 40 a distance sufficient to have its inner face flush with the inner face of the side-wall 35 in which it is mounted and as is especially well shown in Fig. 6. By bearing against the relatively-thin cylindrically-contoured forward portion of the transverse passage 38, the head 44 serves to retain the bolt-depressing arm 40 of which it forms a part against forward lengthwise displacement, while permitting the desired vertical swinging movement of the said arm, as indicated by broken lines in Fig. 5. Furthermore, the rear portion of the periphery of the head 44 bears against the rear portion of the passage 38 and, in conjunction with the cylindrically-contoured rear end 41 of the arm 40 of which it forms a part, serves to absorb violent shocks and prevent the rearward displacement of the said bolt-depressing arm.

In assembling a given bolt-depressing arm 40 with the housing 34, the rear end of the arm in question is inserted rearwardly (with the notch 42a facing inwardly) into the chosen recess 37 so that the retaining-ribs 42-42 of the arm fit into the complementary retaining-grooves 39-39. The rearward movement of the arm is continued until its cylindrically-contoured rear end 41 abuts against the rear wall of the transverse passage 38 in the chosen side-wall 35. The retaining-stud 45 is now installed through the inner end of the transverse passage 38 so that its head 44 seats in the notch 42a of the arm 40 and the shank 46 of the retaining-stud extends through the bore 43 in the bolt-depressing arm. The

outer end of the shank 46 is now headed over into the slightly countersunk outer end of the bore 43 in the arm 40 so that the stud 45 becomes a rigid unitary part of the said arm.

As thus assembled, the given bolt-depressing arm 40 is free to swing to a small degree about the axis of the retaining-stud 45 as a pivot and is retained against forward longitudinal displacement by the engagement of the periphery of the relatively-large head 44 with the relatively-thin forward wall of the transverse passage 38. By virtue of the longitudinal retaining-ribs 42-42 fitting within the retaining-grooves 39-39, the lateral displacement of the given bolt-depressing arm is prevented while permitting the pivotal movement above referred to.

Upon the discharge of the machine gun and in a manner well understood in the art, the barrel 16, barrel-extension 17 and breech-bolt 18 will move rearwardly relative to the receiver 15, housing 34 and the remaining relatively-stationary parts of the machine gun. This movement will carry with it the locking-bolt 27 which will remain in its upper or breech-bolt-locking position until its forward lower corner reaches registration with the downwardly-and-rearwardly-sloping rear face of the lifting-lug 33 which is rigid within the central lower portion of the receiver 15, as before explained. At about the time that the locking-bolt 27 reaches a position where its forward lower corner is in registration with the sloping face of the lifting-lug 33, the actuating-pins 29-29 of the locking-bolt will engage with the rearwardly-and-downwardly-inclined cam-surface 48 of the respective bolt-depressing arms 40-40. If by the time the actuating-pins 29-29 engage with the respective cam-surfaces 48-48, the locking-bolt 27 has not been moved downwardly, then the engagement just referred to will effect the downward movement of the said locking-bolt in a positive manner.

In absorbing the shock of the engagement of the actuating-pins 29-29, the forward portions of the respective bolt-depressing arms 40-40 will be supported against undue upward displacement by the complementary upper wall of the adjacent clearance-recess 31 in the lug 24 of the barrel-extension 17. The shock of the actuating-pins 29-29 engaging the respective bolt-depressing arms 40-40 will also be transmitted lengthwise of the said arms to the rear portions of their respective passages 38-38 which also serve, as previously pointed out, to prevent the bolt-depressing arms 40-40 from being rearwardly displaced.

When during their rearward movement the barrel 16 and barrel-extension 17 reach the positions in which they are shown in Fig. 3, the locking-bolt 27 will be fully depressed, thereby freeing the breech-bolt 18 for continued rearward movement into substantially the position in which it is shown in Fig. 3, while the said barrel and barrel-extension are checked, after but a relatively-slight rearward movement, in substantially the position in which they are shown in the said Fig. 3.

By means of the present invention, though relatively slight in physical aspects, machine guns are enabled to perform satisfactorily and at high rates of speed, since the shocks imposed upon the bolt-depressing or bolt-actuating arms 40 are so well distributed in the housing 34 or its equivalent that the loosening of the said arms to any material extent is guarded against and there-

fore the performance of the machine gun is made consistent and reliable.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A machine gun including in combination: a receiver; an axially-movable barrel; a barrel-extension united with the rear of the said barrel and reciprocating in the said receiver; a breech-bolt associated with the said barrel-extension and movable therewith and also movable longitudinally with respect thereto in a direction lengthwise of the machine-gun structure; a locking-bolt carried by the said barrel-extension and movable vertically with respect thereto to lock and unlock the said breech-bolt to and from the said barrel-extension; a vertical wall-portion located in the said receiver to the rear of the said barrel-extension and having a longitudinal recess therein opening through one side of the said wall-portion and also intersecting the forward end thereof, the said wall-portion also having a transverse passage extending therethrough in intersecting relationship with the rear of the said longitudinal recess; a bolt-actuating arm having a rear-portion fitting within the recess in the said wall-portion and having a forward-portion projecting forwardly into position to engage with a portion of the said locking-bolt to actuate the latter, the rear-portion of the said bolt-actuating arm being formed with a transverse bore registering with the transverse passage in the said wall-portion and having a diameter materially less than the diameter of the said transverse passage; a retaining-stud comprising a relatively-large-dia-metered head having a rotating fit in the transverse recess in the said wall-portion, the said retaining-stud also having a relatively-small-dia-metered shank secured in the transverse bore in the rear portion of the said bolt-actuating arm, the head-portion of the said retaining-stud being tightly held by the said shank against the side face of the arm which faces toward the recess in the said wall-portion; and retaining-means independent of the said retaining-stud and holding the said actuating-arm in the recess in the said wall-portion against lateral displacement therefrom.

2. A machine gun including in combination: a receiver; an axially-movable barrel; a barrel-extension united with the rear of the said barrel and reciprocating in the said receiver; a breech-bolt associated with the said barrel-extension and movable therewith and also movable longitudinally with respect thereto in a direction lengthwise of the machine-gun structure; a locking-bolt carried by the said barrel-extension and movable vertically with respect thereto to lock and unlock the said breech-bolt to and from the said barrel-extension; a vertical wall-portion located in the said receiver to the rear of the said barrel-extension and having a longitudinal recess therein opening through one side of the said wall-portion and also intersecting the forward end thereof, the said wall-portion also having a transverse passage extending therethrough in intersecting relationship with the rear of the said longitudinal recess; a bolt-actuating arm

having a rear-portion fitting within the recess in the said wall-portion and having a forward-portion projecting forwardly into position to engage with a portion of the said locking-bolt to actuate the latter, the rear-portion of the said bolt-actuating arm being formed with a transverse bore registering with the transverse passage in the said wall-portion and having a diameter materially less than the diameter of the said transverse passage; a retaining-stud comprising a relatively-large-dia-metered head having a rotating fit in the transverse recess in the said wall-portion, the said retaining-stud also having a

5 relatively-small-dia-metered shank secured in the transverse bore in the rear portion of the said bolt-actuating arm, the head-portion of the said retaining-stud being tightly held by the said shank against the side face of the arm which faces toward the recess in the said wall-portion; and 10 longitudinally-extending interfitting-rib-and-groove retaining-means independent of the said retaining-stud and holding the said actuating-arm in the recess in the said wall-portion against lateral displacement therefrom.

THOMAS R. ROBINSON, JR.
